UNITED STATES PATENT OFFICE.

JOHN A. READE, JR., AND CHARLES F. BIRTMAN, OF CHICAGO, ILLINOIS.

DESIGN FOR A CABINET-STAND FOR ELECTRIC MOTORS.

SPECIFICATION forming part of Design No. 36,608, dated October 27, 1903.

Application filed August 20, 1903. Serial No. 170,234. Term of patent 7 years.

To all whom it may concern:

Be it known that we, JOHN A. READE, Jr., and CHARLES F. BIRTMAN, citizens of the United States, residing at Chicago, in the county of Cook and State of Illinois, have invented a new, original, and ornamental Design for Cabinet-Stands for Electric Motors, of which the following is a specification, reference being had to the accompanying drawings, forming part thereof.

Figure 1 is a view in side elevation of a cabinet-stand, showing our new design. Fig. 2 is a plan view thereof, and Fig. 3 is a similar view of the base.

What we claim, and desire to secure by Letters Patent, is—

The ornamental design for a cabinet-stand for electric motors, as shown.

In testimony whereof we have signed our names in the presence of two subscribing witnesses.

JOHN A. READE, JR.
CHARLES F. BIRTMAN.
